UNITED STATES PATENT OFFICE.

EDWARD H. JOHNSON, OF NEW YORK, N. Y.

ELECTRIC SWITCH.

SPECIFICATION forming part of Letters Patent No. 448,431, dated March 17, 1891.

Application filed March 27, 1885. Serial No. 160,383. (No model.)

To all whom it may concern:

Be it known that I, EDWARD H. JOHNSON, of New York city, in the county and State of New York, have invented a certain new and 5 useful Improvement in Electrical Switches, of which the following is a specification.

The object I have in view is principally to produce a switch for controlling electrical circuits, which will act to make and break circuit with a quick movement, so as to avoid the arcing at contacts which may be produced by a slow movement. This I accomplish by the employment of one or more powerful springs located between the handle of the 10 switch and the moving contacts thereof, and so connected with such parts that the springs will first be put under tension by the movement of the handle and when the tension is at the maximum point will act upon such 15 moving contacts independent of the handle and will throw such moving contacts in one direction or the other with a quick powerful movement.

My object is further to provide a simple 20 and compact construction of switch embodying this principle, and to apply the principle to a double pole-switch, as well as to improve the form of the contacts, giving large surface and a considerable conducting capacity.

30 In the accompanying drawings, forming a part hereof, Figure 1 is a plan view of the switch with the operating-handle removed, the circuits controlled by the switch being open; Fig. 2, an elevation of the switch with the handle in section, the switch being closed; Fig. 3, a top view of the moving contact-piece, its operating-stem being in horizontal section, and Fig. 4 a bottom view of the handle.

A is a base of insulating material, upon 35 which are mounted four metal binding-posts B B' and C C', the switch shown being designed for a double pole-switch, for making and breaking both sides of the circuit simultaneously. The conductors of one side of 40 circuit run to posts B B', while those of the other side of the circuit run to the posts C C'. From the post C a horizontal stationary contact-plate a extends nearly to post C', and from C' beneath said plate a a similar 45 plate a' extends nearly to C. Between the lapping plates a a' are the shorter plates b b', which are in the same plane and extend

nearly to the center of the space separating the posts, but do not meet. Posts B B' have similar long contact-plates a a' and short ones 55 b b'.

The moving contact-piece is composed of a central hub D of insulating material and two metal arms E E', projecting on opposite sides therefrom and electrically separated by the 60 hub. Each of these wings is split horizontally, and the two parts enter between the plates a a' and b b'. The circuit is closed as soon as the arm strikes the plates a a'; but it is not until the arm reaches the central position that the plates b b' are connected, giving 65 the full carrying capacity of the switch. So in breaking circuit the connection between plates b b' is first broken and then that between plates a a'. When the moving contact-piece is in the position shown in Fig. 1, the circuit is open. When at right angles to 70 that position the circuit is closed. A stop c of insulating material limits the movement of the contact-piece.

75 The mechanism for throwing the moving contact by a quick powerful action is the principal feature of the invention, and will now be described. There are three parts to this mechanism, each capable of movement 80 independent of the others—the contact-piece already described, the spring-eccentric, and the handle. A central stem F passes through the hub D of the contact-piece into the base. Above the contact-piece it turns in a cross- 85 strap d, which is secured to two studs e e' rising from base. The stem turns loosely in hub D for a limited distance, a key f on the stem, Fig. 3, playing in a slot g in hub and permitting this limited independent movement. Between the hub D and strap d the stem is formed into two cranks G G', which are connected by links h h' with the upper 90 ends of powerful spiral springs H H', placed upon studs e e', and having their lower ends 95 secured in the base, as shown in dotted lines in Fig. 2. The stem with its cranks and springs forms the spring-eccentric referred to.

Upon the upper end of the stem F, above 100 strap d, is the handle I. This handle is secured loosely to the stem and has slots i on its under side which engage with pins on a collar k, secured rigidly to the stem. These slots permit a limited movement of the spring-

eccentric independent of the handle. The handle is free to remain in any position to which it is moved, so that the switch will retain either position and will maintain the circuit either made or broken.

The operation of the mechanism is as follows: To throw the contact-piece from the position shown in Fig. 1 to one at right angles closing the circuit, the handle is turned 10 to the left. The cranks turning draw upon the springs and continue to increase the tension on such springs until the cranks are brought into line with the links, the centers being then in line. A slight further movement throws the cranks over the center and releases the springs, and the cranks now under control of the springs are thrown forward in the same direction with a quick powerful action, the stem turning away from the 15 handle. The movement permitted of the stem in the hub of the contact-piece causes such piece to remain stationary during the first part of the movement of the handle, the contact-piece being under the control of the 20 springs and free from the handle in making and breaking circuit. To break circuit the reverse movement of the handle will be made, the springs being first put under tension, and then when the line of centers is passed, released and throwing the contact-piece. It 25 is evident that this movement has great advantages independent of the particular form of switch with which it is used, and I desire to be understood as claiming this movement 30 for switches generally without limitation to the special details of the switch shown and described.

What I claim is—

1. A hand-switch for making and breaking 40 an electric circuit having, in combination, a moving contact-piece, a spring connected with said moving contact-piece by a loose connection, and a free handle connected with such spring and acting by its movement to strain 45 the spring and to release it without making or breaking the circuit, whereby the spring will then throw the moving contact-piece by direct spring action to the end of its movement, and the circuit will be made or broken 50 by a spring-snap action, substantially as set forth.

2. A hand-switch for making and breaking an electric circuit having, in combination, a moving contact-piece, a spring connected with 55 said moving contact-piece by a loose connec-

tion and adapted to throw it when strained and released by direct spring action to the end of its movement, and a free handle connected with such spring by a loose connection and acting by its movement to strain the 60 spring and to release it without making or breaking the circuit, whereby the spring will then throw the moving contact-piece independent of the handle and the circuit will be made or broken by a spring-snap action, substantially as set forth.

3. A hand-switch for making and breaking an electric circuit having, in combination, a pivoted contact-piece, a spring connected eccentrically thereto by a loose connection, and a free handle connected with such spring and adapted to move its bearing-point across the line of centers without making or breaking the circuit, whereby the spring will be strained and released and will move the contact-piece 75 and make or break the circuit by a spring-snap action, substantially as set forth.

4. A hand-switch for making and breaking an electric circuit having, in combination, a pivoted contact-piece, a spring connected eccentrically thereto by a loose connection, and a free handle connected with such spring by a loose connection and adapted to move its bearing-point across the line of centers without making or breaking the circuit, whereby the spring will be strained and released and will move the contact-piece independent of the handle and make or break the circuit by a spring-snap action, substantially as set forth.

5. A double pole-switch having, in combination, two sets of stationary contacts, a contact-piece pivoted between them and having insulated metallic arms which bridge the contacts of the two sets by the turning movement of the pivoted contact-piece, and a spring-eccentric throwing such contact-piece in both directions, substantially as set forth.

6. In an electrical switch, the combination, with the pivoted contact-piece, of the lapping stationary contacts in different planes and the approaching stationary contacts in the same plane, substantially as and for the purpose set forth.

This specification signed and witnessed this 19th day of March, 1885.

EDWARD H. JOHNSON.
